UNITED STATES PATENT OFFICE

156,616

COMBINED SALT AND PEPPER SHAKER

Robert W. Gish, Napa, Calif.

Application January 31, 1948, Serial No. 144,202

Term of patent 3½ years

(Cl. D44—22)

To all whom it may concern:

Be it known that I, Robert W. Gish, a citizen of the United States of America, residing at Napa, in the county of Napa, and State of California, have invented a new, original, and ornamental Design for a Combined Salt and Pepper Shaker, of which the following is a specification, reference being made to the accompanying drawings, forming a part thereof.

Fig. 1 is a top-plan view of a salt and pepper shaker showing my new design;

Fig. 2 is a side elevational view; and

Fig. 3 is an end elevational view thereof.

I claim:

The ornamental design for a combined salt and pepper shaker, substantially as shown.

ROBERT W. GISH.
